CLAIM

The ornamental design for a surgical instrument, as shown and described.

DESCRIPTION

FIG. 1 illustrates a front perspective view of a surgical instrument;

FIG. 2 illustrates a front elevation view of the surgical instrument of FIG. 1;

FIG. 3 illustrates a back elevation view of the surgical instrument of FIG. 1;

FIG. 4 illustrates a side elevation view of the surgical instrument of FIG. 1, note that the surgical instrument of FIG. 1 is shown in an enlarged scale in FIG. 4;

FIG. 5 illustrates a side elevation view of the surgical instrument of FIG. 1, note that the surgical instrument of FIG. 1 is shown in an enlarged scale in FIG. 5;

FIG. 6 illustrates a top plan view of the surgical instrument of FIG. 1, note that the surgical instrument of FIG. 6 is shown in an enlarged scale in FIG. 6; and,

FIG. 7 illustrates a bottom plan view of the surgical instrument of FIG. 1, note that the surgical instrument of FIG. 1 is shown in an enlarged scale in FIG. 7.

The features shown in broken lines depict environmental subject matter only and are in the drawings for the purpose of illustrating portions of the surgical instrument that form no part of the claimed design.
